HAT BOW

Oscar Regen, New York, N. Y.

Application March 28, 1936, Serial No. 71,398

6 Claims. (Cl. 2—181)

This invention relates to the manufacture of hats, especially to a sweat band, and more particularly to means for finishing the seam uniting the abutting ends of the sweat-leather.

5 In the manufacture of leather sweats for hats, it is the custom to unite the abutting edges of the ends of the leather either by sewing across the seam or by applying adhesive behind the seam, after which an ornament, such as a bow tassel is applied, by a separate operation, to the junction point where the seam intersects the free inner margin of the leather.

An object of the present invention is to save one step in the above operation by the provision 15 of a bow, tassel, or other ornamental device with a flexible stretch of material comprising a cord, or pair of cords, a ribbon or braid, which constitutes a pre-formed, unitary article of manufacture that can be applied as such to the seam 20 of the sweat leather by laying the flexible stretch of material along the seam so that when the seam is sewed the stitching secures to the abutting edges of the leather the stretch of cord, ribbon or braid, in such fashion that it will either 25 overlie the adjacent margins of the abutting edges or will lie in the plane of the joint therebetween.

In either event the cord, ribbon or braid ornaments the junction. Many different styles of 30 bows or tassels may be used, the invention not being limited in this respect.

A cognate object of the invention is to provide for the preformation of the article by so tying the bow over the stretch of cord, ribbon or braid 35 that the sewing operation which is required in fixing the cord to the seam will serve to secure the bow to the leather.

It will be understood by those skilled in the art that inasmuch as it is the province of the 40 hat manufacturer to join into circular bands the leathersweats which he has bought in the form of strips that have been cut, and then to stitch each circular band into its hat, the present invention facilitates the preparation of the circular band by providing the bow and ornamental 45 stretch of cord or the like in convenient form to use in the seam-forming operation upon individual bands.

50 Other objects and features of the invention will appear as the description of the particular physical embodiment selected to illustrate the invention progresses.

In the accompanying drawing, like characters 55 of reference have been applied to corresponding

parts throughout the several views composing the drawing, in which:

Fig. 1 is a view in perspective elevation looking into a hat toward the rear seam of a leathersweat in the construction of which the present invention has been embodied;

Fig. 2 is a fragmentary, detail view on an enlarged scale of the seam shown in Fig. 1;

Fig. 3 is a view in horizontal, transverse section, on a still larger scale, taken on the line 3—3 10 of Fig. 2;

Fig. 4 is a detail view in vertical sectional elevation, illustrating a modification to be described.

Fig. 5 is a view, similar to Fig. 3, of another 15 modification.

In a now-preferred embodiment of the invention, selected for illustration, the part designated by the reference character 11 is a hat, of which 20 12 is the leathersweat having a seam 13 surrounded by a bow or ornament 14 at the intersection between the seam and the free margin of the sweat.

Referring now more particularly to Figs. 2 and 3, it will be seen that the margins 15 and 25 16 of the leather 12 have their edges brought together, as at 17 (see Fig. 3) in abutting relation, to form the upright seam requisite to give the leather the form of a circular band, preparatory to stitching it into the hat, as indicated at 18. 30

As hereinbefore noted briefly it is the province of the hat manufacturer to perform the step of so uniting the edges of the margins, then applying separately a bow or ornament, as 14, and then stitching the circular band into the hat.

If the joint 17 is secured by a row of stitches, this is usually accomplished by an operation separate from that of attaching the bow 14.

In contradistinction to this practice, the present invention provides a bow 14, (which may in 40 general structure be of the usual form) with a novel attachment 19 comprising a stretch of flexible material, such as cord, ribbon or braid, which is adapted and intended to be secured by a row of stitches 20, of any suitable character, in 45 such fashion as to constitute an ornamental finish for the seam 17, and to that end it may be disposed to overlie the seam, as shown in Figs. 2 and 3 most clearly, or it may be disposed in the plane of the joint, between the adjacent edges of 50 the marginal portions 15x and 16x, substantially as illustrated in Fig. 5 of the drawing, where the stretch of cord is designated 21x, 22x and the stitches 20x.

In pursuance of the invention, the stretch 19 55

of ornamental cord, ribbon, braid, or any suitable material, is secured to the bow 14 in order to constitute the bow and stretch a unitary structure, forming an article of manufacture which 5 can be sold in quantities to makers of hats, ready for application to individual leathers at the time they are formed into the circular form preparatory to being stitched into the hat, as already indicated.

10 Preferably the stretch 19 will be made double, having elements 21, 22 with a loop 23 in the bight of which can be tied the strip of which the bow 14 is made up, and thus when the usual tying of the bow is performed to fix the bow in final form, 15 this operation will serve at the same time to secure the cord to the bow, at the region of the loop 23.

In practice, it has not been found necessary to 20 secure the elements 21, 22 together before applying the combined bow 14 and ornamental cord 19 to the leather, as the sewing machine operator can readily lay the elements side by side during the operation of stitching.

The effect produced is very ornamental and 25 can be varied indefinitely by choosing materials of different colors, twist, etc. for the cord 19, and by using thread for the stitching 20 which is of contrasting color to that of the elements 21, 22. The ornamental effect can be varied still further 30 by the substitution, at 14, for the bow shown in Figs. 1 and 2, of a tassel or the like, as that illustrated at 24 in Fig. 4, either with or without a bow element, such as that shown at 14' in Fig. 4.

In this figure a single cord, ribbon or braid 19' 35 is illustrated, instead of the pair shown at 21, 22 in Fig. 2, but it will be understood that the structure of the seam will be similar to that shown in Figs. 1 to 3, and already described, with such variations as may appeal to the individual manufacturer, or may be desirable with different forms 40 of joints.

I have described what I believe to be the best 45 embodiments of my invention. I do not wish, however, to be confined to the embodiments shown, but what I desire to cover by Letters Patent is set forth in the appended claims.

I claim:

1. The combination with a sweat band for a 50 hat formed of strip material having its end edges joined in a seam, of a finish element preformed with an ornamental stretch of stranded flexible material extended along said seam and secured to the adjacent margins of the seam by stitching extended along said seam and embracing said 55 stretch throughout the mutually extending length of said edges and the stretch of ornamental stranded flexible material.

2. The combination with a sweat band for a 60 hat formed of strip material having its end edges joined in a seam, of a bow, and an ornamental stretch of flexible stranded material associated with said seam, and secured to the adjacent mar-

gins of the edges by stitching uniting said stretch with said edges, throughout their mutually extending length said ornamental stretch overlying said margins.

3. The combination with a sweat band formed 5 of strip material having its end edges joined in a seam, of a finish element and an ornamental stretch of flexible stranded material, associated with said seam, and secured to the adjacent margins of the edges by stitching uniting said edges, 10 said ornamental stretch of stranded material lying in the plane of the seam, between the adjacent end edges of the band.

4. The combination with a sweat band formed 15 of strip material having its end edges joined in a seam, of a bow, and an ornamental stretch of cord, associated with said seam, throughout its length and secured to the adjacent margins of the edges by a row of transverse stitches uniting 20 said edges, and embracing said stretch of cord, said stretch comprising a plurality of cord elements respectively overlying the band material side by side along said seam and concealing the latter.

5. As a new article of manufacture; a pre- 25 formed ornament for the sweat band of a hat; said ornament comprising in a unitary structure, adapted to be sold as such, for application to the sweat band, the combination of a finish element and a stretch of ornamental stranded ma- 30 terial conjoined permanently therewith; said finish element and flexible strand constituting together a complete entity adapted to be associated at will with the conventional seam joining the adjacent ends of the sweat band, by being 35 extended along said seam and secured to the margins of said adjacent end edges by a row of stitches spanning said edges and embracing said stretch of flexible strand, throughout the length of said seam, said finish element consists of a 40 bow having a knot with a strand interlooped with a loop of said flexible strand.

6. As a new article of manufacture; a pre- 45 formed ornament for the sweat band of a hat; said ornament comprising in a unitary structure, adapted to be sold as such, for application to the sweat band, the combination of a finish element and a stretch of ornamental stranded material conjoined permanently therewith; said finish element and flexible strand constituting together a 50 complete entity adapted to be associated at will with the conventional seam joining the adjacent ends of the sweat band, by being extended along said seam and secured to the margins of said adjacent end edges by a row of stitches span- 55 ning said edges and embracing said stretch of flexible strand, throughout the length of said seam, the ornamental stretch formed with a loop in the bight of which the strip component of said bow is tied, and the stretch having a plurality 60 of strands extending from said loop.

OSCAR REGEN.
